HIGHWAY SIGNAL

Filed Sept. 5, 1936

UNITED STATES PATENT OFFICE

2,105,203

HIGHWAY SIGNAL

Thornton J. Simpson, Chula Vista, Calif.

Application September 5, 1936, Serial No. 99,597

4 Claims. (Cl. 177—329)

The present invention relates to railway crossing signalling apparatus.

It is one of the objects of the invention to produce, adjacent to a railway crossing, a combination of intersecting light beams which appear to a driver approaching such crossing, high above the road bed.

It is one of the important objects of the invention to produce adjacent a railway crossing a pair of moving light beams originating at opposite sides of the roadway, which will appear to a motorists approaching such crossing as intersecting high above the road bed and which will more effectively warn him of the danger of approaching trains.

It is a further important object of the invention to provide a spectacular widely sweeping movement of elevated light beams operating similarly to the movement of the arms of a semaphore, which will be clearly visible to motorists and will arrest their attention while they are still at a considerable distance from the crossing and notwithstanding the presence of curves, dips or crests and other obstructions in the highway adjacent to the crossing.

It is a still further object of the invention to provide a two-part signalling device positioned at diagonally opposite corners of a railway intersection, each of which will cast a light beam both upwardly and downwardly across a highway intersecting the railway and will appear to an approaching motorist as a light beam barrier, the downwardly bent beams being directed upon warning indicia conspicuously placed in the center of the highway.

Among other objects of the invention are: to condense and simplify apparatus to which the invention appertains; to provide for the production of moving signals that will be visible at a greater distance from the crossing; to support the signalling elements in a superior, oscillatable manner; to provide unique circuit making and breaking means for actuating the signals upon the approach of trains in the vicinity of the crossing; to provide a novel combination of elements; and to provide a very positively actuated and dependable railway crossing signal.

A somewhat more specific object of the invention is the provision of a lamp having rays projectible across a highway intersecting a railway, which are rockable as a semaphore from one extreme position to another, providing conductors for the lamp which are closable by the span of the wheels of a train traveling on said railway, having a branch parallel circuit in which the con-

ductors of the lamp are included, and means and mechanism for operating the lamp and at the same time holding open the parallel circuit during the functioning of the lamp.

Still other objects, advantages and features of invention will hereinafter appear.

Railroad and highway intersections of today are provided with a variety of signals for indicating warnings to drivers of the hazards that may be encountered both by safe and reckless drivers. None of these signals are standardized for respective crossings and it is not uncommon to find a pair of swinging gates which form an obstructing barrier at one point while a short distance away at a less hazardous point only a wig-wag is used and oftentimes on less traveled streets and roads no warning indication whatsoever is provided.

It is not uncommon today for the rate of speed of a traveling vehicle to be such as to cause it to bear down on an approaching train before time is had for the driver to bring the vehicle under control. This is partly due to the fact that the crossing signal is not discernible at a sufficient distance from the intersection, or turns in the road, or hills or dips, making such a signal obscure. For these reasons, and many others, a more conspicuously visible crossing signal is needed. This invention is suited to meet the aforesaid need.

Referring to the accompanying drawing, which illustrates what at present is deemed to be a preferred embodiment of the invention,

Fig. 1 is a perspective view showing the apparatus installed at a railway crossing, the wiring connections with the rails of the track being illustrated diagrammatically.

Fig. 2 is an enlarged perspective view of one of the signal casings and parts contained therein, all of which commonly relate to the signal structures shown at the right and left side of Fig. 1, some parts being omitted and others broken away to disclose interior working parts. In this view also, a portion of the wiring is shown diagrammatically.

Fig. 3 is a schematic diagram of the electrical circuit.

Referring in detail to the drawing, the main parts of the apparatus are duplicated at each side of the highway 5 on opposite sides of a railway 50 intersecting the same, that is to say at diagonally opposite corners of the crossing. These parts include the posts 6, cross bars 7, brace bars 8, and cruciate signal frames 9. As viewed in Fig. 1 the right frame 9 rigidly supports a signal casing 55

10 and the left frame 9 likewise supports a signal casing 11. The structures mounted within these two casings are identical and hence only those within the right hand casing 10 will be described 5 in detail.

Casing 10 is shown in Fig. 2 with its cover plate 12, containing the conventional signal lens 13, removed.

To the rear wall of the casing 10, which is 10 mounted upon the cruciate frame 9 in any suitable manner, is fastened an L-shaped block of insulating material 14, into the longer bulged leg of which is screwed a stud shaft 15. A bracket 16 having a hollow sleeve bearing 17 is rockably 15 mounted on the shaft 15 and the sleeve is retained in its rockable position by means of a collar 18 and a screw 19 fed therethru and tapped into the exposed end of said shaft. Into the outer wall of the sleeve 17 is fastened tripping means 20 comprising an upstanding bakelite pin 20 which as the bracket is rocked in turn is operated to swing back and forth from one extreme position to another.

The bracket 16 has L-shaped limbs or shelf 25 supporting arms 21 and 22 emanating from the sleeve 17 which are preferably disposed at a right angle to each other. The free limb of the arm 21 supports a concavo-convex reflector 23 on which is mounted an electric lamp 24 in an up- 30 standing relation thereto, and the free limb of the arm 22 likewise supports a concavo-convex reflector 25.

On the rear face of the free limb of the arm 22 is an extension 26 which is pivotally connected 35 by a pin 27 to the core 28 of the solenoid 29. The solenoid core is fastened to the piston 30 thru the medium of the stem 31, and the piston is slidably mounted in the dash pot cylinder 32 fastened to the wall of the casing. Mounted in 40 the dash pot beneath the piston is a spring 33 which opposes the travel of the core into the dash pot.

A switching arrangement is mounted on the block 14 which opens and closes the circuit to the 45 solenoid and comprises flexible copper strips 34 and 35 fastened to the shorter leg of said block by means of screws 36 constituting binding posts to which are applied the nuts 37.

A switch rod 38 slidably mounted in the bracket 50 39 fastened to the insulating block 14 is actuated to the left and right by the pin 20, said pin having a lost motion action within a cut away portion of said rod. The slidable switch rod, on being pushed to the left by the pin 20 thru the 55 reaction of the spring 33, contacts both copper strips thereby closing the circuit thru the solenoid 29 whereupon the solenoid pulls down on the core 28 against the opposition of spring 33. Part 38 stays between strips 34 and 35 until the other 60 end of the stroke is reached whence pin 20 pulls rod 38 to the right and breaks the solenoid circuit. Then spring 33 returns the piston to its upper position and the operation is repeated, ad infinitum, so long as the circuit is completed thru the 65 main leads which will be described more completely later.

In the upper wall of the casing 10 is an elongated window 40 which is positioned to disclose the oscillating light ray 41 from the reflector 23, 70 and through the adjacent left hand wall of the casing is a window 42, the position and size of which enable it to disclose the light rays 43 from the reflector 25 at all times during its oscillation. It will be observed that both of these light rays 75 are produced by the lamp 24. The rays 41 are

projected at an upward inclination to a considerable height above the roadway, while the rays 43 are cast downwardly and upon the "Stop" signs upon the roadbed.

The reflectors 23 and 25 are positioned angularly with relation to each other and both of them are arranged to reflect light beams from the lamp 24, the light beams from reflector 23 at all times during its oscillation being directed at an upward inclination thru window 40 while the 10 light beams from reflector 25 at all times during its oscillation are directed at a downward inclination thru window 42.

The upwardly as well as the downwardly cast light beams appear as intersecting to a motorist 15 approaching the crossing from a distance.

Thus a light beam barrier having a repeated semaphoric shifting is cast across the roadway as a warning to motorists that a train is either approaching or leaving the vicinity of the inter- 20 section.

The rails of the double track are shown consecutively numbered 44, 45, 46 and 47, and are broken away at each side of the crossing to indicate the remote circuit-completing means 25 operated by trains approaching from either direction.

Electricity to operate the device is supplied by line wires 48 and 49. The wire 48 is furnished with a lead 50 which goes directly to the lamp 24. 30 The other lamp lead 51 is connected to a conductor 52 which electrically connects rails 45 and 47, that is to say the right hand rails of both tracks, assuming that the observer is looking toward the left in Fig. 1. The line wire 49 is furnished with 35 a lead 53 which is connected to a conductor 54 that unites the remaining two rails 44 and 46. Insulation blocks 55 are shown which are placed between adjacent rail ends sufficiently distant from the crossing to provide that drivers of approaching vehicles be warned in due time.

It has been stated that the line wire 48 has a lead 50 which goes to the lamp 24. Said lead 50 has a branch 56 which is connected with one end of the solenoid, the opposite end of said solenoid 45 having a lead 57 going to the copper strip 34. The copper strip 35 is furnished with a lead 58 going to lead 51, already mentioned, which cooperates with the conductor 52 and track rails 45 and 47 to complete that line of the circuit. If 50 a train passes over the section of either track which is segregated by insulation, wires 54 and 52 are connected thru the span of the train's wheels and the circuit is completed causing the lights to operate.

Operation.—The oscillating portion of the device is shown in the center of the swinging arc including arcs N' and N, and spring 33 is raising piston 30 and solenoid core 28. Near the end of the stroke, pin 20 will slide rod 38 to the left and contact is made between parts 34 and 35 causing solenoid 29 to pull down on the core 28. Part 38 stays between parts 34 and 35 until the other end of the stroke is reached whence pin 20 pulls slider 38 to the right and breaks the solenoid circuit. After this operation spring 33 returns the piston up and these operations are continued so long as the wheels close the circuit between rails within the sections of rails segregated by the insulations 55.

The slider element afforded by rod 38 may be varied in shape so long as it is provided with a cut away portion or suitable means to afford a lost motion connection between it and pin 20.

It shall be understood that, although the pres- 75

ent disclosure is based on a preferred modification, it is for the purpose of illustration only and that this invention includes all other modifications and equivalents which fall within the scope 5 of what is claimed.

What is claimed is:

1. In a crossing signal, a lamp, a rockable support therefor, a plurality of reflectors mounted upon said support, said reflectors being positioned angularly with relation to each other and both of them being arranged to reflect light beams from said lamp, and means to automatically oscillate said support, the light beams from one of said reflectors at all times during its oscillation being directed at an upward inclination and the light beams from the other said reflector at all times during its oscillation being directed at a downward inclination.
2. In a signal adjacent a crossing, a lamp, a rockable support therefor, reflectors positioned angularly with relation to each other mounted upon said support, said reflectors being positioned to reflect light beams from said lamp at different angles simultaneously in a plane at right angles to said crossing, and means to automatically oscillate said support whereby to project a

semaphoric movement of said light beams across said crossings.

3. In a crossing signal, a casing, windows disposed in adjacent walls of said casing, a pivotal support mounted in said casing, a frame rockably mounted on said support, said frame comprising a sleeve concentric to said pivotal support, a pair of angularly shaped brackets depending from said sleeve, each of said brackets having a light reflecting surface, a lamp mounted upon one of said reflecting surfaces, and means to rock said frame and thereby cause a swinging movement of the light beam reflected thereby thru said windows.

4. In a crossing signal, a casing, windows disposed in adjacent walls of said casing, a pivotal support mounted in said casing, a frame rockably mounted on said support, a pair of angularly shaped brackets depending from said frame, each of said brackets having a light reflecting surface, a lamp mounted upon one of said reflecting surfaces, and means to rock said frame and thereby cause a swinging movement of the light beam reflected thereby thru said windows.
